UNITED STATES PATENT OFFICE.

TAM KOTRUS, OF CLEVELAND, OHIO.

FOLDING CHAIR FOR TABLES OR THE LIKE.

1,227,803.

Specification of Letters Patent.

Patented May 29, 1917.

Application filed August 4, 1913. Serial No. 113,145.

To all whom it may concern:

Be it known that I, TAM KOTRUS, a subject of the King of Hungary, residing at Cleveland, in the county of Cuyahoga and State of Ohio, have invented certain new and useful Improvements in Folding Chairs for Tables or the like, of which the following is a specification.

This invention relates to certain new and useful improvements in folding chairs for tables or the like.

The primary object of the invention is the provision of a folding chair structure attached to a table or other support whereby the chair may be positioned out of the way when not desired for use although readily shiftable to its operative position at a side of the table when required.

A further object of the device is the provision of a chair attachment specially adapted for use in connection with restaurant tables and wherever it is desired to economize space, the present chairs being readily positioned in folded arrangement beneath the table when normally arranged inoperatively.

With these general objects in view and others that will appear as the nature of the invention is better understood, the same consists in the novel construction, combination and arrangement of parts hereinafter more fully described, illustrated in the accompanying drawings, and then claimed.

In the drawing forming a part of this application and in which like designating characters refer to corresponding parts throughout the several views:—

Figure 1 is a side elevation of a table provided with the present device partially broken away.

Fig. 2 is a top plan view thereof.

Fig. 3 is a detail sectional view taken upon line III—III of Fig. 1.

Fig. 4 is a detail view of the retaining spring latch, parts being broken away, and,

Fig. 5 is an elevational view of a portion of the outer rail of the table showing the latch arranged thereon.

The invention is herein illustrated in connection with a table 10 having a top 11, corner supporting legs 12 and a rectangular frame formed of side rails 13, the chairs broadly consisting of paddle-shaped members, the circular outer ends 15 of which constitute seats, and the shank portions 16 of

which are hinged at their free ends as at 17 to the adjacent rail 13.

A back member 18 is provided for the seats 15 and has spindles 19 slidably arranged through the seat 15 which spindles 60 carry a locking block 21 upon the ends thereof beneath the said seat.

A single leg 22 is provided for each of the seats 15 being hinged therebeneath upon lugs 23 while a leaf spring 24 is carried by 65 the said lugs normally engaging the adjacent side of the leg 22 assisting in retaining the leg in perpendicular arrangement beneath the seat 15, as best illustrated by the seat shown at the left of the table in Fig. 1 70 of the drawing. The leg 22 is provided at its pivoted end with a notch 25 adapted for the reception of the block 21, the arrangement of the said block within said notch being shown at the left side of Fig. 1 when the 75 seat is unfolded and placed in its operative position, the spindles 19 of the back 18 being withdrawn through the seat member 15 and the block 21 engaging the lower face of said notch whereby the leg 22 is held in operative 80 position by the tension of spring 24.

When the chair is folded, the seat member is moved upon its hinge 17 to a substantially vertical position, as illustrated at the right hand side of Fig. 1 and the leg 22 is swung 85 inwardly and upwardly beneath the table by means of its hinge connection with the lugs 23 and the spindles 19 of the chair back 18 is forced through the seat 15 for engaging the block 21 within the notch 25 of 90 the leg 22 whereby reason of the close frictional engagement of the spindles 19 with the seat 15, the block is maintained seated within the notch 25 retaining the leg 22 in its upright folded position with its free end 95 in substantial contact with the inner face of one of the side rails 13 of the table 10.

A latch 26 right-angular in form is pivoted as at 27 beneath the rail 13 adjacent the chair so as to position the engaging end 100 28 of the latch back of the leg 22 when the latter is folded for insuring the retention of the chair in its folded position, as illustrated at the right in Fig. 1. A spring-pressed catch 29 is carried by the outer handle 30 of the latch 26 for retaining the latch in its adjusted position by engaging within a socket in a mounting boss 31 for the latch pivot 27.

An auxiliary circular seat 32 may be at 110

tached by a central screw 33 with one of the seats 15 if desired as illustrated in Figs. 1 and 2 of the drawing, the remainder of such chairs being identical to those heretofore described. Where the foldable chair having the shiftable back 18 is employed for household use, the projecting portion of the chair back 18 which is arranged adjacent the floor 34 when the chair is folded 5 may be employed for a seat for children, it being noted that the back 18 at such times is substantially positioned beneath the projecting edge of the table top 11 arranged thereabove so that the chairs when folded 10 lie substantially within the confines or space taken up by the table 10. A foldable chair arrangement is thus provided serviceable both for domestic purposes as well as restaurant use providing a compact chair structure 15 readily operable by the user.

What I claim as new is:—

1. A device of the class described comprising in combination with a support, a seat hinged thereto, a supporting leg hinged beneath the said seat and 25 having a notch adjacent the lower face of the seat, and a chair back shiftable carried by the said seat in restraining engagement within the said notch when the seat and leg 30 are in their folded arrangement.

2. A device of the class described comprising a support, a seat hinged thereto, a supporting leg hinged beneath the said seat and shiftable to substantially parallel relation 25 therewith and provided with a notch adjacent the under face of the said seat, a chair back shiftable arranged through the rear portion of the said seat, a locking block carried by the said back beneath the 40 said seat, said block being seated within

the said notch and in contact with the said seat when the latter is horizontally positioned, the said block being adapted to be lockingly arranged within the said notch and spaced from the said seat when the seat 45 and leg are in folded position.

3. A device of the class described comprising a table having a top and a side rail therebeneath, a seat hinged to the outer face of the said rail, a supporting leg hinged beneath the said seat, a chair back shiftable arranged through the said seat, a locking block carried by the said back beneath the said seat, the said leg being provided with a receiving notch adjacent the said block, the 50 said block being seated within the said notch with the chair back shiftable positioned partially through the said seat when the said seat and leg are foldably arranged substantially vertically beneath the table top with 55 the said back in a horizontal position.

4. A device of the class described comprising a table having a top and a side rail, a seat hinged to said side rail, a leg hinged beneath the said seat adjacent the free end 60 thereof, the free end of the said leg being arranged in contact with the inner face of the said rail substantially parallel with the said seat when the device is folded, the said leg having a receiving notch adjacent the 65 said seat, a back member for the seat shiftable arranged therethrough, and a locking block upon the said back member between the said leg and seat arranged within the 70 said notch when the device is folded with the back member in its horizontal seat forming arrangement.

In testimony whereof I affix my signature.

TAM KOTTUS.
